UNITED STATES PATENT OFFICE.

WILLIAM CAIRNS, OF CHICAGO, ILLINOIS.

DESIGN FOR A REAR BRACKET FOR BICYCLES.

SPECIFICATION forming part of Design No. 30,822, dated May 16, 1899.

Application filed April 21, 1899. Serial No. 713,975. Term of patent 7 years.

To all whom it may concern:

Be it known that I, WILLIAM CAIRNS, a citizen of the United States, residing at Chicago, in the county of Cook and State of Illinois, have invented and produced a new and original Design for a Rear Bracket for Bicycles; and I do hereby declare the following to be a full, clear, and exact description of the same, reference being had to the accompanying drawings, forming a part of this specification, in which—

Figure 1 is a side elevation of the bracket; and Fig. 2, a top view of the same, partly in horizontal section, at line $x x$, Fig. 1.

The present invention relates to a design for the bracket, which constitutes the connecting member for the rear forks of a chainless bicycle and is adapted to afford a bearing for the axle of the rear driving-wheel; and the said invention consists in the structural configuration hereinafter described and as illustrated in the accompanying drawings.

The present improved bracket comprises a main body portion 1 of a circular or ring form in side elevation and cylindrical in cross-

section. At its forward end the body portion 1 is provided with a horizontally and substantially radially arranged intersecting cylindrical sleeve or socket 2 for the attachment of the horizontal rear fork or frame member, near its upper end with a projecting lug 3 for the attachment of the oblique rear fork or frame member, and at its rear end with a transversely-arranged hub portion 4 for the reception of the axle of the rear driving-wheel, the whole constituting one integral piece.

The essential features of the present invention are the ring or cylindrical annulus, the intersecting radial socket, attaching-lug, and transversely-arranged hub.

I claim—

The design for a rear bracket for a bicycle-frame, substantially as shown.

In testimony whereof witness my hand this 17th day of April, 1899.

WILLIAM CAIRNS.

In presence of—

ROBERT BURNS,
JAMES LAVALLIN.
